(57) **CLAIM**

We claim the ornamental design for an elevated dog bowl, as shown and described.

DESCRIPTION

FIG. 1 is a perspective view of an elevated dog bowl.
 FIG. 2 is a perspective view of the claimed design from below.
 FIG. 3 is an exploded view of the claimed design showing a removable bowl of the elevated dog bowl separated from a base of the elevated dog bowl.

FIG. 4 is a front elevation view of the claimed design.

FIG. 5 is a rear elevation view thereof.

FIG. 6 is a left-side elevation view thereof.

FIG. 7 is a right-side elevation view thereof.

FIG. 8 is a top plan view thereof; and,

FIG. 9 is a bottom plan view thereof.

The features depicted in broken line are not claimed.
